UNITED STATES PATENT OFFICE.

WILLIAM C. KEYWORTH, OF PATERSON, NEW JERSEY.

MACHINE FOR WINDING, LUSTERING, AND FINISHING SILK, &c.

No. 872,734.

Specification of Letters Patent.

Patented Dec. 3, 1907.

Application filed March 1, 1906. Serial No. 303,601.

To all whom it may concern:

Be it known that I, WILLIAM C. KEYWORTH a citizen of the United States, residing at Paterson, in the county of Passaic 5 and State of New Jersey, have invented certain new and useful Improvements in Machines for Winding, Coloring, Lustering, and Finishing Silk and other Fibrous Materials, of which the following is a specification, 10 reference being had therein to the accompanying drawing.

In an apparatus for lustering and finishing silk thread or filaments and yarn or thread of other materials, means are provided for 15 treating the filaments collectively, to a suitable liquid bath in a vessel adapted therefor, and for drying and lustering them by passing them over a heated surface after they emerge from the bath, the surplus moisture having been removed by means provided 20 for that purpose prior to their arrival at the heated surface over which they travel.

One object of my invention is to improve the art by treating the threads or filaments 25 independently, each in its individual bath, thus permitting the finishing and lustering of threads or filaments of many or various colors simultaneously on the same machine.

Other improvements for this purpose will 30 be hereinafter described and pointed out in the claims.

Another object of my invention is to make one machine do the work of two, one side of the machine being a duplicate of the other, 35 thus increasing the production at a reduced cost and with a saving in floor space.

Another and important object of my invention is to produce a machine that will 40 not only accomplish the above named objects but will as well perform the work of a winding machine, a branch of manufacture now performed by machines adapted only for the purpose of winding, thus obviating altogether the use of such machines and accomplishing a great saving in machinery, time, 45 labor and floor space.

Briefly, I provide a machine that winds, lusters, finishes and if need be, colors the threads or filaments in one continuous operation or process.

My process consists in drawing the silk thread or other filament from the skein, immersing it in and drawing it through, a suitable liquid bath, removing the surplus moisture therefrom and carrying it over a heated

surface and spooling or winding the same on a suitable receiver.

In my invention the thread or filament is wound from the skein onto a winding bobbin, and is colored, finished and lustered during its passage thereto.

If it is desired to redraw the thread or filament to improve the material for future processes of manufacture, the machine illustrated in the accompanying drawing, which 65 embodies my invention, will permit of the redrawing, finishing and lustering of certain threads or filaments and the winding, finishing and lustering of certain other threads or filaments at the same time. It is therefore 70 obvious that my machine can take the place of a winding-frame, a redrawing-frame and a finishing and lustering machine with great saving and economy.

In the drawing, Figure 1, is a view in 75 vertical cross-section of a machine embodying my invention. Fig. 2, is an enlarged view in central vertical longitudinal section of an individual basin showing rollers, knife brush and liquid bath. Fig. 3, is a side elevation 80 showing means for driving the machine and reciprocating the rocking-bar.

In the machine herein illustrated —a— represents the thread or filament which is wound from the skein on the swift —8—, is 85 passed under a roller —24— which is removably mounted in grooves —25— in the basin —22—, then immersed in the liquid —23—, drawn over the knife —26—, brush —27— and removable roller —28— and to the 90 curved heated surface —11—, which may be heated by steam, hot water, hot air, gas or electricity as preferred, over which it is carried and around the adjustable tension rollers —16— and —18— on lever-arms —17— 95 and —19— respectively, thence to guide in traverse-bar —5— and onto the suitably mounted winding bobbin —4— which is driven by the friction pulley —3— on the shaft —2— mounted on the frame —1—. 100 The shaft —2— is driven by belt and pulley —31— and the bevelled gears shown in Fig. 3 by dotted lines.

The pinion —10— on the end of shaft —2— meshes with and turns the gear —9— and 105 cam —6— to reciprocate the traverse-bar —5— and distribute the finished and lustered thread or filament on the winding bobbin —4—.

The thread —a— if desired, may be re- 110

drawn from a bobbin —7— to a bobbin —4—, or from a bobbin —7— through the bath and over the heated surface to the bobbin —4—. The bath may be removed and the thread or 5 filament —a— may be wound from the swift onto the bobbin —4—. Hence my machine may be employed as conditions arise, either for a winding machine, a redrawing machine, or for a lustering and finishing machine; or 10 for a redrawing, refinishing and relustering machine; or, for a winding, finishing and lustering machine. From the construction shown and described, it will be seen that all of the said operations may be going on at the 15 same time in a single machine; that as each thread or filament has its individual bath, threads or filaments of different colors may be treated without injury to the colors, which would occur if many threads of different 20 colors were passing through the same bath; that if desired coloring matter might be mixed in a bath to suit the coloring of the thread or filament passing or to be passed through said particular bath, thus winding, 25 coloring, finishing and lustering the thread or filament in one continuous operation.

The bars —20— support the basin —22— and a collar —21— serves as an adjusting device for basin—which has shoulders —30— 30 adapted to rest on the bars —20—. Boxes —29— to hold bobbins are secured to the machine - frame—extending longitudinally therewith on both sides thereof. Heat is furnished through the supply pipes —12— and —14— and circulates through the return pipes —13— and —15—.

The lever-arms —17— and —19— may be adjusted to and fixed at any desirable angle in relation to the heated surface —11— for 40 the purpose of determining the extent of contact the thread or filament has with said heated surface—and to regulate the tension of the thread or filament passing over the rollers —16— and —18— which are mounted 45 in the outer ends of said lever-arms.

The surplus moisture is removed from the thread or filament as it emerges from the liquid bath by the knife —26— and brush —27— which are held in suitable supports or 50 brackets inside the basin —22— above the surface of the liquid. Both the knife and the brush may be removed and cleaned as often as is necessary.

The roller —24— is removable and the tension of the thread or filament —a— causes the spindle of said roller to turn in the journal formed by the extreme end of the angle-grooves —25— on the inner sides of the basin. 55

The sides of the basin —22— extend beyond 60 the end thereof and the roller —28— is mounted to turn so that the thread or filament may pass down between said extended sides clear of the end of the basin.

To prevent the accumulation of matter 65 that fouls the heating surface in machines of

this kind, I provide the knife and brush and provide a heated surface that has no edges to come in contact with the thread or filament after it has passed the brush and knife which substantially clean it as it leaves the bath. 70

Means for regulating the delivery or supply of the thread or filament from the swift may consist of the ordinary weight 78 as shown in Fig. 3, or other suitable device.

The individual heating surfaces and baths 75 facilitate the manipulation of the threads or filaments, and avoid the trouble, delay and expense resulting from the simultaneous treatment of a mass of threads or filaments in the same bath, and traveling over the same 80 heated surface,—owing to the massing of the wet threads or filaments, the tangling and breaking and searching for the broken ends.

As is clearly shown in Fig. 3, my machine permits free and unobstructed access to 85 each and every thread or filament from the time it leaves the swift until wound upon the receiving bobbin.

My machine may be constructed of any length and capacity to meet the requirements of the trade. A manufacturer may not have the floor space for a large machine and one may be made accordingly.

Many mechanical changes and modifications may be made in my machine without 95 departing from the scope and essential spirit of my invention, and I wish to claim, and do claim the benefit of all advantages and uses for which my machine is suitable, even though some of said advantages or uses may 100 not have been enumerated or described in this specification.

With this description of my invention, what I claim as new and desire to secure by Letters-Patent, is:—

1. In a machine for winding, lustering and finishing silk thread or fiber, the combination with a frame and thread-carriers mounted thereon, of a series of individual basins for liquid below the same, one for the treatment 110 of each thread or fiber as it comes down from its spool or carrier, a series of vertically arranged, individual heating bodies below said basins, one for each thread or filament, and means for causing each thread to travel vertically on both sides of its heating body after leaving its basin, and thence on to its receiving spool, for the purposes specified, and substantially as set forth.

2. In a machine for winding, lustering and finishing silk thread, a frame, delivering and receiving spools mounted thereon in combination with a series of individual basins for liquid, one for the treatment of each thread, a series of vertically arranged individually 125 heating bodies located below said basins, one for each thread, and means for winding each thread upon its receiving spool as it is drawn from the basin and about its heating body, and causing each of said individual threads 130

to travel in a separate and substantially parallel course, from start to finish, substantially as set forth.

3. In a machine for finishing silk threads, 5 a frame, a removable basin for containing liquid in which the thread is to be immersed, adjustably held thereon, in combination with removable and revoluble rollers mounted in said basin, a knife and a brush, both removable, and carried in said basin above the surface of the liquid and arranged substantially as set forth.
4. In a machine for finishing silk thread, a plurality of skein-carrying members and 10 winding bobbins, in combination with a plu- 15

rality of basins provided with rollers, brushes and knives arranged as shown, a plurality of heated bodies over which the threads are caused to travel, and means for drawing a series of silk threads in substantially parallel 20 courses from the skein-carrying members, through the basins, over the heated bodies and to the winding bobbins.

In testimony whereof I affix my signature in presence of two witnesses.

WILLIAM C. KEYWORTH.
